UNITED STATES PATENT OFFICE.

HORACE T. THOMAS, OF LANSING, MICHIGAN, ASSIGNOR TO REO MOTOR CAR COMPANY,
OF LANSING, MICHIGAN, A CORPORATION OF MICHIGAN.

STARTER.

1,142,285.

Specification of Letters Patent. Patented June 8, 1915.

Application filed July 5, 1912. Serial No. 707,754.

To all whom it may concern:

Be it known that I, HORACE T. THOMAS, a citizen of the United States, residing at Lansing, county of Ingham, State of Michigan, have invented a certain new and useful Improvement in Starters, and declare the following to be a full, clear, and exact description of the same, such as will enable others skilled in the art to which it pertains to make and use the same, reference being had to the accompanying drawings, which form a part of this specification.

My invention relates to starters for internal combustion engines and an object of my improvement is to provide an improved starter in which acetylene gas is used. I secure this object in the device illustrated in the accompanying drawings, in which,

Figure 1, is a horizontal section of a portion of the device embodying my invention, the section being upon the line 1—1 Fig. 2. Fig. 2 is a side elevation of the same partly cut away on the line 2—2 Fig. 1. Fig. 3, is a section on the line 3—3 Fig. 1. Fig. 4, is an elevation partly in section of a portion of an automobile with an internal combustion engine mounted thereon, and the apparatus embodying my invention secured in its proper place. Fig. 5, is a detail plan view of the apparatus adjacent to the dash-board.

Referring to Fig. 4 of the drawings, X, is the frame of an automobile. Z, indicates the internal combustion engine mounted thereon. A, is a tank containing acetylene or other combustible gas under pressure. B, is the intake passage to the cylinders of the engine Z. C, is the dash-board. D, is a casing mounted on the dash-board and forming a casing in which the mechanism hereinafter described is placed. a, is a conduit pipe leading from the reservoir A to an aperture in the casing D. b, is a pipe forming a conduit leading from a chamber b¹ (Fig. 3) in the casing D to the intake pipe B.

In the chamber b¹ (Fig. 1) is located a valve seat E on which fits the valve e. This valve is held normally in place upon its seat by a spring F.

G, is a rod adapted to reciprocate in a passage in the casing D and to contact the valve e to force the same away from its seat. g, is a disk or pedal secured to the outer end of the rod G and adapted to be actuated by the foot of the operator, or otherwise. The rod G is provided with a

notch q (Fig. 2), and there is a slidable plate Q, which, when the rod G is forced inward may slide upward and engage in the notch q to hold the rod in this position and the valve e away from its seat. When the plate Q is released from the notch q, the spring F will force the valve e back to its seat and the rod G outward to its normal position.

Y, (Fig. 4) is an ignition magneto. R, (Figs. 5 and 1) is a contact strip secured on the dash-board C. r, is a conducting wire connected to a pole of the magneto Y and to the strip R. S, is a pin extending transversely through the rod G and through slots in the casing D, said rod being provided with a head s. When the rod G is pressed inward to displace the valve e, the head s contacts the strip R and grounds the magneto so that it shall not act to fire the charges in the cylinder.

The casing D is provided with a cylindrical portion T, which has a bore J in which may reciprocate a piston K. This piston is mounted upon a rod L, which rod bears in the casing and guides said piston. The bore J is provided with screw threads at its outer end, in which engages a screw threaded cap P through which cap the rod L passes coaxial therewith. M, is a compression spring interposed between the piston K and the inner surface of the cap P. N, is a compression spring interposed between an outer surface of the cap P and a pin n passing through the outer end of the rod or stem L. H, is a valve seat surrounding an aperture axially in line with the rod or stem L. h, is a valve upon the valve seat H. i, is a compression spring acting to hold the valve h upon its seat. The inner end of the stem or rod L is normally held a little ways away from the valve h but when the piston K is drawn inward, it carries with it the rod L forcing its end against the valve h and displacing the latter from its seat.

The chamber b¹ communicates by a transverse passage j with the inner end of the bore J of the cylindrical portion T.

It will be noticed that the pressure of gas from the tank A passes through the pipe a and is continually acting upon the valve H, its pressure tending to hold said valve to its seat.

It will also be noticed that the valve e normally closes communication between the intake pipe B of the engine through the pipe

b and the portion of the interior of the casing *D* beyond said valve.

The operation of the above described device is as follows: When the automobile reaches its destination, the operator presses in on the rod *G* thus short-circuiting the magneto, the engine turning a few revolutions by reason of its inertia and then stopping. By pressing in the rod *G*, the valve *E* is displaced upon its seat and the suction of the engine then acts to draw the piston *K* inward and displace the valve *h* permitting combustible gas to flow through the pipe *a* into the casing *D*, through the passage *j* 10 into the chamber *b*¹ and through the pipe *b* to the intake *B* of the engine where it forms an explosive mixture and enters the cylinders. When the operator desires to start the engine, he completes the battery circuit 15 and the mixture will be ignited in the cylinders and the engine started. As long as the valve *e* is off its seat, an explosive mixture of the gas from the reservoir *A* will be drawn into the cylinder and the engine will 20 continue to operate. When it is in motion, the rod *G* is released permitting the valve *e* to return to its seat and cutting off connection of the engine through the pipe *b*. The engine will then run normally drawing its 25 supply in the usual way through the intake pipe *B*.

The amount of combustible gas drawn in through the casing *D* in the operation of the above described apparatus is regulated 30 by turning the cap *P* and thus moving said cap along the bore *J* of the cylindrical portion *T*, thus adjusting the position of the *L* relative to the valve *h*.

What I claim is:—

1. The combination of an internal combustion engine having an intake passage, of a reservoir for gas under pressure, a passage adapted to form a communication between said intake and said reservoir, a valve controlling the passage between said reservoir and said intake, a second valve adapted to control the passage between said intake and said reservoir between the first named valve and the intake, means for manipulating said 45 second valve to open the passage between the intake and the first named valve, said first named valve being adapted to be actuated by the suction of the engine.

2. The combination of an internal combustion engine having an intake passage, of a reservoir for gas under pressure, a passage adapted to form a communication between said intake and said reservoir, a valve controlling the passage between said reservoir and said intake, a second valve adapted to control the passage between said intake and said reservoir between the first named valve and the intake, means for actuating said sec-

ond valve to open the passage between the intake and the first named valve, and means 65 adapted to be actuated by the suction of the engine, for actuating the first named valve.

3. The combination of an internal combustion engine having an intake passage, a reservoir for gas under pressure, a passage 70 adapted to form a communication between said intake and said reservoir, a valve controlling the passage between said reservoir and said intake, means adapted to be actuated by the suction of the engine for actuating said valve, and means for adjusting the action of said means for actuating the valve. 75

4. The combination of an internal combustion engine having an intake passage, a reservoir for gas under pressure, a conduit 80 adapted to connect said intake pipe and said reservoir, a non-return valve *h* adapted to control the passage through said conduit opening toward said reservoir, a cylindrical portion *T* having a piston adapted to reciprocate therein, said piston being adapted to contact said valve to force the same from its seat and a passage forming a part of said conduit between the intake passage and said valve opening beneath said piston. 85

5. The combination of an internal combustion engine having an intake passage, a reservoir for gas under pressure, a conduit adapted to connect said intake pipe and said reservoir, a non-return valve *h* adapted to 90 control the passage through said conduit opening toward said reservoir, a cylindrical part *T* having a piston adapted to reciprocate therein, said piston being adapted to contact said valve to force the same from its seat, a passage forming a part of said conduit between the intake passage and said valve opening beneath said piston, a spring governing the motion of said piston, and means for adjusting the position of said piston and spring relative to said valve. 95

6. The combination of an internal combustion engine having an intake passage, a reservoir for gas under pressure, a conduit 100 adapted to connect said intake pipe and said reservoir, a non-return valve *h* adapted to control the passage through said conduit, said valve being so arranged that the pressure of the gas from said reservoir shall act to press said valve toward its seat, and means adapted to be actuated by the suction of the engine for forcing said valve from its seat to permit the passage of a limited 105 amount of said gas.

In testimony whereof, I sign this specification in the presence of two witnesses.

HORACE T. THOMAS.
